US00D975289S

(12) **United States Design Patent** (10) **Patent No.:** **US D975,289 S**
Zimmermann (45) **Date of Patent:** **** Jan. 10, 2023**

(54) **MEDICAL DEVICE FOR FETAL MONITORING**

(71) Applicant: **VIEWCARE TECHNOLOGIES 1 APS**, Soborg (DK)

(72) Inventor: **Henrik Zimmermann**, Aarhus (DK)

(73) Assignee: **VIEWCARE TECHNOLOGIES 1 APS**, Soborg (DK)

(**) Term: **15 Years**

(21) Appl. No.: **29/836,376**

(22) Filed: **Apr. 26, 2022**

Related U.S. Application Data

(62) Division of application No. 35/509,946, filed on Jan. 27, 2020 (U.S. filing date under 35 U.S.C. 384), and having an international filing date of Jan. 27, 2020, now Pat. No. Des. 953,543.

(57) **CLAIM**

The ornamental design for a medical device for fetal monitoring, as shown and described.

DESCRIPTION

FIG. 1 is a perspective view of a medical device for fetal monitoring.

FIG. 2 is a front view of the medical device for fetal monitoring.

FIG. 3 is a rear view of the medical device for fetal monitoring.

FIG. 4 is top view of the medical device for fetal monitoring.

FIG. 5 is a right side view of the medical device for fetal monitoring.

FIG. 6 is a left side view of the medical device for fetal monitoring; and,

FIG. 7 is a bottom view of the medical device for fetal monitoring.

The broken lines shown in one or more of the figures are for the purpose of illustrating portions of the medical device for fetal monitoring and form no part of the claimed design.

1 Claim, 5 Drawing Sheets
